UNITED STATES PATENT OFFICE.

ERNEST R. ZIMMERMAN, OF CHICAGO, ILLINOIS.

COMBINED MOP AND WRINGER.

1,126,930.

Specification of Letters Patent.

Patented Feb. 2, 1915.

Application filed October 3, 1914. Serial No. 864,708.

To all whom it may concern:

Be it known that I, ERNEST R. ZIMMERMAN, a citizen of the United States, residing at Chicago, in the county of Cook and State 5 of Illinois, have invented a certain new and useful Improvement in Combined Mops and Wringers, of which the following is a specification.

My invention relates to combined mops 10 and wringers and the general object of the invention is to provide a device of this class which shall be simple in form and durable and capable of manipulation with the least possible effort on the part of the user.

Among the specific objects of the invention are: first, to provide a device of this class in which the wringer is unlocked when the mop is in wringing position but becomes automatically locked when the mop is 20 brought to scrubbing position. Second, to provide a construction such that the center of gravity of the device as a whole is shifted materially inward when the parts are brought to wringing position thus making 25 the device much easier to manipulate and reducing the apparent weight thereof in the hands of the user. Third, to provide a construction such that the mop may hang substantially vertical when in wringing position, while the handle remains approximately horizontal thus making the device easier to handle. Fourth, to provide means 30 for limiting the inswing of the mop when in wringing position thus avoiding any danger of the mop touching the clothing of the user during the act of wringing. Fifth, to provide means for limiting the up swing 35 of the mop relatively to the handle.

I accomplish my objects by the mechanism illustrated in the accompanying drawings in which—

Figure 1 is a side elevation of the mop and wringer in acting position. Fig. 2 is a side elevation showing the parts in wringing position. Fig. 3 is a plan view of the parts as shown in Fig. 1, the handle being omitted in order to better reveal the construction of the parts beneath. Fig. 4 is a sectional detail on the line 4—4, Fig. 3. 50 Similar numerals refer to similar parts throughout the several views.

At the lower end of the handle 1 is an extension consisting in the present form of

arms 2, preferably two in number, fastened to the handle by a socket or ferrule 3 or 55 other suitable means. By preference said extension consists of a single bifurcated casting, as shown. A frame is connected by pivots 4 to the handle extension at a point between the ends of the arms 2. At the 60 lower end of the arm 5 of the frame is a loop 6 for supporting the outer end of the mop 7. The inner end of the mop is supported by a hook or loop 8 formed at the outer end of a shaft 9 journaled in the bearing 10 formed at the lower end of the arm 11 of the pivoted frame. It is desirable that the parts be so configured that shaft 9 and the arm 5 of the pivoted frame will lie approximately parallel to each other on opposite sides of the pivots 4. Shaft 9 is rotated 65 by a crank 12 provided with a handle 13, and the arrangement is such that when the parts are in acting or scrubbing position said crank will extend upward from shaft 9, 70 passing between the two branches of the handle extension and being thus locked between said branches; but when the mop is permitted to drop to wringing position, the pivoted frame will swing the crank up clear 75 of said branches and permit the crank to be rotated.

The mop is held to its work by a foot which, in the present design, consists of a base 15 having an arm 16 at the inner end 85 and an eye 17 at its outer end. The arm 16 is connected by the pivots 18, 18 to the outer end of the arms 2. The eye 17 encircles the arm 5 of the pivoted frame at the outer end. The sliding movement of said eye upon arm 5 is limited by a stop 19 formed upon arm 5. As the crank 12 passes up between the branches of the handle extension, the up swing of the mop from scrubbing position might well be limited by the crank itself abutting the crotch of said extension. Or, the movement might be limited by the handle 13 striking the top of said extension. It is preferable, however, to provide special stops for limiting the up 90 swing. This I accomplish by forming stops 20 on from 5 in position to abut the stops 21 on the arms 2^a of the handle extension when the mop is in scrubbing position as shown in Fig. 1. As a result of these co-operating stops the up swing is limited and 95 100 105

the user may, if desired, cause only the outer or forward end of the mop to exert pressure on the floor. In other words, with my construction it is possible to vary the pressure at different points, producing, at will, greater pressure at the inner end or at the outer end or producing approximately uniform pressure throughout the length of the mop. Another advantage is that by limiting the up swing of the frame 5 the mop may remain comparatively loose for, as the pivots 4 and 18 are located at a distance from each other and the outer end of the presser foot 15 slides on a fixed path along the frame, the up swing of the frame tends to cause the foot to tighten the mop. Hence by thus limiting the up swing of the frame, the tightening of the mop is limited and the mop may be so proportioned as to leave it quite loose when the device is in scrubbing position. A loose mop does its work better than a tight one, and hence my device has a decided advantage in this respect.

In operation, when the mop is in use it will be held to the floor by the foot and will be held extended through the coöperation of the loop 6 on arm 5 and the hook 8 on shaft 9. It will be noted that the foot is pivoted to the handle extension at a point beyond the pivots 4. The result is that the portions 2^a of the arms 2 act as levers to swing the inner end of the foot away from arm 5 when the mop is in acting position, the eye 17 acting as a pivotal point about which the foot swings toward or from the arm 5. When the user wishes to immerse the mop or wring it, he simply lifts the handle, whereupon gravity acting upon the mop and its supports causes the parts to drop to the position shown in Fig. 2. There are several advantages in this; first, as the parts swing to vertical position the center of gravity moves toward the hand of the user and hence the weight of the device does not seem as great as it would if the parts remained approximately horizontal, as shown in Fig. 1. Second, this position is very convenient for it renders it easy to lower the mop into the bucket or other vessel containing the water for scrubbing. Third, it unlocks the handle. Fourth, it brings the crank into a convenient position to be rotated. As the eye 17 slides along the arm 5 it approaches the stop 19, which is so placed as to arrest the down swing of arm 5 when the parts reach approximately a vertical position, as shown in Fig. 2. The portions 2^a of the arms 2 cause the foot to move away from the mop when the parts swing to wringing position, thus permitting the mop to be wrung without being hindered by the foot.

It will be noted that my device is of simple construction and of few parts and has little

in it to get out of order. It is convenient to operate and locks and unlocks the crank automatically and at the same time dispenses with bevel gears and all other types of toothed wheels.

Having thus described my invention, what I claim as new and desire to secure by Letters Patent, is:—

1. A combined mop and wringer comprising a pivotally supported member having means at the outer end to which the mop may be attached, and a shaft having means to which the other end of the mop may be attached, said shaft being journaled in said pivotally supported element.

2. In a device of the class described, the combination of a handle having an extension, a frame supporting the outer end of the mop, a wringer shaft journaled in said frame, and a crank for rotating said shaft, said frame being pivoted to the handle extension to permit the handle to be brought into and out of the plane of rotation of the crank.

3. In a device of the class described, the combination of a bifurcated extension, a crank shaft attached to the inner end of the mop, a crank for rotating said shaft, and a frame supporting the outer end of the mop, said frame being pivoted to the handle extension at a point a short distance from the crooth of the extension, a journal bearing on said frame for supporting said shaft, said journal bearing being remote from the frame pivot to enable it to bring a portion of the crank between the arms of the extension when the device is in scrubbing position, to thereby lock the crank against rotation.

4. In a combination mop and wringer, the combination of a handle, a bifurcated handle extension, an L shaped frame, a pivot for connecting the frame to the handle extension, said pivot being located approximately at the bend of the frame and remote from the crotch of the handle extension, a journal bearing carried by said frame at a point remote from said journal, said bearing being arranged approximately parallel with the longer leg of said frame, crank shaft journaled in said bearing, a crank extending from said shaft upward between the branches of the handle extension when the parts are in scrubbing position, said journal bearing being far enough from said pivot to swing the crank clear of the handle and handle extension when the parts are brought to scrubbing position, and a mop attached at one end to said shaft and at the other end to said frame at a point thereon on the opposite side of the frame pivot from said journal bearing.

5. A combination mop and wringer comprising a handle, a bifurcated handle exten-

- sion, a crank shaft, a crank integral with said shaft, an L shaped member pivotally supported between the branches of said handle extension, said pivot being located 5 near the bend of said L shaped member and remote from the crotch of the handle extension, one leg of said L shaped member being longer than the other, a bearing for said shaft formed at the end of the short leg of 10 said L shaped member, said bearing being below the pivot when the parts are in scrubbing position, and a mop attached at one end to the long leg of the L shaped member and at the other end to said shaft at a point in 15 front of said pivot when the parts are in scrubbing position whereby the weight of the mop tends to cause it and the long leg to drop toward vertical position when lifted from the floor.
- 20 6. A combination mop and wringer comprising a handle, a handle extension, a pivoted element articulately connected to said handle extension at a point remote from the outer end thereof, a journal bearing carried by said pivoted element at a point beneath the handle extension when the parts are in scrubbing position, a shaft journaled in said bearing, means for rotating said shaft, a mop attached to said shaft and to 25 said pivoted element, and a foot pivoted to the outer end of said handle extension, said foot also having a bearing upon said pivoted member.
7. A combination mop and wringer comprising a handle, an L shaped pivoted element pivoted to said handle extension at a point remote from the outer end thereof, one leg of said pivoted element being longer than the other and said legs lying pivotally 30 on opposite sides of the pivot thereof, a journal bearing at the end of the shorter leg, a wringer shaft in said bearing, a mop connected to said shaft and to the outer end of the longer leg of the pivoted element, 35 and a foot pivoted to the end of the handle extension and having a bearing upon the longer leg of said pivoted element.
8. A combination mop and wringer comprising a handle, a handle extension, a frame pivoted to said handle extension at a point remote from the outer end thereof, said frame extending on opposite sides of the frame pivot, a journal bearing at one 40 end of said frame, a mop fastened to the other end of said frame, a shaft attached to the remaining end of said mop, and supported in said journal bearing, and a presser foot pivoted to the outer end of said handle extension and having a sliding bearing 45 upon said frame.
- 60 9. A combination mop and wringer comprising a handle, a bifurcated handle extension, an L shaped frame, a pivot for connecting said frame to said extension, said pivot being located approximately midway 55 between the crotch and the outer end of the handle extension, said pivot being located near the bend of the frame, a journal bearing formed in the shorter leg of the frame, a shaft journaled in said bearing, a crank integral with said shaft and passing up between the branches of the handle extension when the parts are in scrubbing position, a mop attached to said shaft and attached to the longer leg of said frame, and a presser 60 foot pivotally connected at one end to the outer end of the handle extension, said presser foot having a sliding bearing upon the longer leg of said frame.
10. A combination mop and wringer comprising a handle having an extension thereon, a frame pivoted to said extension remote from the outer end thereof, a shaft journaled in said frame, a mop connected to the frame and to the shaft, and a presser foot 65 connected at one end to the frame and at the other end to the outer end of the extension of the handle.
11. A combination mop and wringer comprising a handle having an extension thereon, a frame pivoted to said extension remote from the outer end thereof, a shaft journaled in said frame, a handle rigidly fastened to said shaft, a mop connected at one 70 end to the frame and at the other end to the shaft, a presser foot pivotally connected to the outer end of the extension of the handle and having a sliding bearing upon said frame, and a stop on said frame for limiting the sliding movement of said presser foot.
12. In a combination mop and wringer, a handle, a handle extension, a frame pivoted to said extension at a substantial distance from the outer end thereof, a presser foot 75 backing up the mop, said presser foot being pivoted to the outer end of the handle extension and having a bearing on the frame, and means for limiting the up swing of said frame.
13. In a combination mop and wringer, a handle, a handle extension, a frame pivoted to said extension at a substantial distance from the outer end thereof, a presser foot backing up the mop, said presser foot being pivoted to the outer end of the handle extension and having a sliding bearing on the frame, a suitably supported wringer shaft, a mop attached to said shaft and to said frame, and coöperating stops on the frame 80 and on the handle extension for limiting the up swing of the frame.
14. In a device of the class described, a handle, a handle extension, a frame pivoted to said handle extension at a point remote from the outer end thereof, a wringer shaft journaled in said frame, a mop attached to said shaft and to the forward end of said 85

frame, a presser foot backing up the mop, said presser foot being pivoted to the outer end of the handle extension and being also supported by said frame and means for limiting the up swing of the frame in the handle extension.

In witness whereof, I have hereunto sub-

scribed my name in the presence of two witnesses.

ERNEST R. ZIMMERMAN.
